US00D714793S

(12) **United States Design Patent**
Kim et al.

(10) **Patent No.:** US D714,793 S
(45) **Date of Patent:** ** Oct. 7, 2014

(54) **CRADLE FOR A PORTABLE COMPUTER**

(71) Applicant: **Samsung Electronics Co., Ltd.,**
Suwon-Si (KR)

(72) Inventors: **Jun-Se Kim**, Gwank-gu (KR);
Sang-Won Yoon, Seocho-gu (KR);
Ji-Eun Myung, Eunpyeong-gu (KR);
Nicole Lee, Dongdaemun-gu (KR)

(73) Assignee: **Samsung Electronics Co., Ltd.,**
Suwon-Si (KR)

(**) Term: **14 Years**

(21) Appl. No.: **29/458,176**

(22) Filed: **Jun. 17, 2013**

(30) **Foreign Application Priority Data**

Dec. 28, 2012 (KR) 30-2012-0062734

(57) **CLAIM**

The ornamental design for a cradle for a portable computer, as
shown and described.

DESCRIPTION

FIG. 1 is a top front perspective view of a cradle for a portable computer showing our new design;
FIG. 2 is a front view thereof;
FIG. 3 is a rear view thereof;
FIG. 4 is a left side view thereof;
FIG. 5 is a right side view thereof;
FIG. 6 is a top view thereof;
FIG. 7 is a bottom view thereof; and,
FIG. 8 is a top rear perspective view thereof, but showing an alternate position.

1 Claim, 4 Drawing Sheets
